UNITED STATES PATENT OFFICE.

BIG GEORG YOUNG AND CHARLES N. PICKERING, OF CEDARGROVE,
WEST VIRGINIA.

TROLLEY-WHEEL AND SUPPORT.

Specification of Letters Patent. Patented Oct. 9, 1906.

No. 832,765.

Application filed November 18, 1905. Serial No. 287,112.

To all whom it may concern:

Be it known that we, BIG G. YOUNG and CHARLES N. PICKERING, citizens of the United States, residing at Cedar Grove, in the county of Kanawha and State of West Virginia, have invented certain new and useful Improvements in Trolley-Wheels and Supports; and we do declare the following to be a full, clear, and exact description of the invention, such as will enable others skilled in the art to which it appertains to make and use the same.

This invention relates to improvements in trolley-wheels and supports.

The object of the invention is to provide a device of this character comprising a support having formed in one end an adjustable socket to receive the upper end of the trolley-pole and on its opposite end with a pivotally-mounted forked bearing-bracket to receive the trolley-wheel.

Another object is to provide a trolley-wheel formed in sections and means whereby said sections of the wheel are removably secured to a shaft, which is revolutely mounted in said forked bracket.

A further object is to provide a detachable connection for the upper end of the electrical conductor or cable.

With the above and other objects in view the invention consists of certain novel features of construction, combination, and arrangement of parts, as will be hereinafter described and claimed.

In the accompanying drawings, Figure 1 is a side view of a trolley-wheel and support constructed in accordance with the invention, parts of the same being shown in section. Fig. 2 is an edge view of the same. Fig. 3 is an irregular sectional view on the line 3-3 of Fig. 1. Fig. 4 is a sectional view on the line 4-4 of Fig. 1, and Fig. 5 is a similar view on the line 5-5 in Fig. 1.

Referring more particularly to the drawings, 1 denotes the support, the lower end of which is formed with a tapered socket 2. In two of the opposite sides of said socketed end of the support are formed slits 3, whereby said end of the support may be adjustably clamped to the upper end of the trolley-pole by means of a clamping-bolt 4, thereby permitting the wearing or shrinking of the upper end of the pole to be compensated for.

The upper or opposite end of the support 1 is preferably offset at a suitable angle from the socketed portion of the same, and on said offset upper end of the support is formed a right-angularly-projecting bearing-spindle 5, said spindle being here shown and is preferably integral with the support 1 and is provided with one or more annular grooves 6, as shown. Revolubly mounted upon the spindle 5 is a forked bearing-bracket 7, said bracket being preferably formed in two halves or sections, in the adjacent faces of the lower connected ends of which are formed semicylindrical bearing-surfaces 8. On each of these bearing-surfaces 8 is formed one or more segmental flanges 9, which when the two sections of the bracket are brought together around the spindle 5 are adapted to engage the annular grooves in the latter, thereby preventing the removal of the bracket 2. On the opposite sides of the connected portions of each section of the bracket are formed laterally-projecting apertured ears or lugs, through which are adapted to be passed bolts 12, by means of which the sections of the brackets are secured together.

In the upper forked ends of the brackets 7 are formed alined bearing-apertures 13, in which are arranged bushings 14. In the bushings 14 are journaled the opposite reduced ends of a shaft 15, the enlarged portion of said shaft being threaded, as shown at 16, and on said threaded portion of the shaft 15 is adapted to be screwed a trolley-wheel 17. Said wheel is here shown and is preferably constructed in three sections, a central section 18, forming an engaging surface for the trolley-wire, and two outer side sections 19, forming the flanges of the wheel. By thus constructing the wheel either of said sections when becoming worn may be readily removed and replaced by a new section. On the edges of the forks of the bracket 7 are arranged oil-cups 20, which communicate with the bearings in said forks to lubricate the same.

To the outer offset end of the support 1 is connected the lower end of a coil-spring 21, the opposite end of which is connected to the bearing-bracket 7, whereby when the latter is turned upon the spindle 5 the tension of the spring will be exerted to restore the same to its normal position.

Arranged on one side of the support 1 is a cable-attaching device, by which the upper end of an electrical cable or conductor is secured to the support. The connection here shown is in the form of a sleeve or ferrule 22, on which is formed a right-angularly-projecting threaded shank 23, which is adapted to be screwed into a threaded aperture formed in the side of the socket, as shown.

A trolley-wheel and support constructed as herein shown and described will be found to possess many advantages over the common form of device, and by forming the trolley-wheel of separate detachable sections the same may be kept in perfect working order.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described our invention, what

we claim as new, and desire to secure by Letters Patent, is—

In a device of the character described, the combination with a wheel-support having formed in one end a split tapering socket to receive the end of a trolley-pole, of a bearing-spindle arranged on the upper end of said support, said spindle having formed therein annular grooves, a sectional, forked bearing-bracket pivotally mounted on said spindle, said bracket having formed thereon annular flanges to engage the annular grooves in said spindle, means to removably secure said sections of the bracket together, a shaft journaled in said bracket, a sectional trolley-wheel arranged on said shaft, and means whereby the sections of said wheel are removably connected to the shaft, substantially as described.

In testimony whereof we have hereunto set our hands in presence of two subscribing witnesses.

BIG GEORG YOUNG.
CHARLES N. PICKERING.
